UNITED STATES PATENT OFFICE

MOSES E. CHENEY, OF LA CROSSE, WISCONSIN, ASSIGNEE, BY MESNE ASSIGNMENTS, TO
MOTO METER GAUGE & EQUIPMENT CORPORATION, OF LONG ISLAND CITY, NEW
YORK, A CORPORATION OF DELAWARE

THERMOMETER-BULB-FORMING METHOD

Original application filed March 24, 1928, Serial No. 264,499. Divided and this application filed December 18, 1928. Serial No. 326,776.

This invention relates to an improvement in the method of manufacturing thermometers and more particularly to an improved method of forming the bulb of a metal type and of attaching the capillary tube to said bulb. This application is a division of application Serial No. 264,499 filed March 24, 1928.

The object of the invention is to construct 10 a thermometer bulb that will withstand the severe mechanical strains incident to certain kinds of use, such as when applied to the motor of an automobile or similar uses, where it is subjected to excessive heat, high pressures and considerable vibration, also the strains incident to careless handling.

The method employed herein obviates difficulties heretofore met with in soldering the 20 fragile capillary tube properly to the metal bulb, in that a minimum of area to be soldered is provided by this improved method and any and all separate parts are dispensed with, thereby reducing expense such as the expert skill required in soldering prior devices and 25 simplifying the method of assembling the parts.

Furthermore, the method is peculiarly adapted to the formation of a thermometer wherein an armored member is employed to 30 protect the capillary against accidental bends and sharp turns; for the particular method herein employed not only a stronger bulb than those heretofore used but it forms an inner surface especially adapted to the 35 armored member and the solder that is required to hold the capillary properly within the bulb. For this and other reasons, the method consists in a general way of forming the bulb from a single sheet of metal which 40 is first formed into a cartridge shaped receptacle having one end closed, which thereafter by a series of drawing, punching and spinning operations is worked into a tube having the open end partially closed by forming 45 a very much reduced portion intermediate the body and the end and a slightly reduced portion beyond the said intermediate portion, thereby presenting a bulb structure of one piece, but having a neck and a chamber of 50 proper size extending beyond the neck, the

inner walls of the chamber and neck being of such a conformation as to form a pocket for the lower end of the armored member and for the solder, while the neck also forms a bearing for centering the capillary tube.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

Figure 1 is a view of the tube of cartridge shape, while Fig. 2 shows the tube bulged near one end; Fig. 3 shows the intermediate neck portion and chamber partially formed. Fig. 4 shows the parts assembled in position while Fig. 5 is an enlarged view showing the conformation of the inner surfaces of the 75 neck and chamber.

The bulb marked 1 is preferably formed of copper or other workable metal and by a series of operations such as punching, drawing and spinning the sheet of metal first assumes the shape shown in Fig. 1 and is thereafter brought into the final shape shown in Figs. 5 and 6, as fully set forth in the co-pending application, the flange 2 (Fig. 2) is preferably first formed and thereafter the reduced neck portion 3 (Figs. 5 and 6).

As shown clearly in Figs. 5 and 6 the inner surface of the open end of the tube is of a double or reverse curve and might be described as a cyma reversa curve wherein the convex part constitutes the neck and the extreme lower part of the chamber 4 while the concave part forms the adjacent part of the tube proper and this form of curve forms a centering portion for the capillary tube and also a pocket for the solder marked 5 which is desirable for securing the parts within the tube, the armored member being marked 6. It is likewise apparent that there is a reduced area for soldering as compared with 100

prior devices, thereby eliminating the care and skill required when large areas are soldered. Consequently, the completed article has a portion eminently suited to the function 5 of centering the capillary and the adjacent portions diverge from that central point and project on each side making the bulb especially desirable as a container for the capillary and medium to be used therein.

10 Figs. 3 and 4 illustrate an alternative method of forming the neck portion 3 and cup 4. In this latter method the reduced neck portion 3, (see Fig. 3) is formed first, and subsequently the cup 4 is reduced as shown in 15 Fig. 4. It has been found desirable in certain adaptations of the thermometer bulb to omit forming the shoulder 2 thereon and in these cases the intermediate step of forming the shoulder may be advantageously omitted 20 in expediting production.

Without further analysis, the foregoing will so fully reveal the gist of this invention that others can, by applying current knowledge, readily adapt it for various utilizations 25 by retaining one or more of the features that, from the standpoint of the prior art, fairly constitute essential characteristics of either the generic or specific aspect of this invention and, therefore, such adaptations should 30 be, and are intended to be, comprehended within the meaning and range of equivalency of the following claim.

Having thus revealed this invention, I claim as new and desire to secure the following 35 combinations and elements, or equivalents thereof, by Letters Patent of United States:—

The method of forming a metal thermometer bulb from integral bulb blanks having closed and open ends by first reducing 40 the part adjacent the open end for forming a neck intermediate the open and closed ends, thereafter drawing and spinning said neck portion until the inner walls of said neck 45 form smooth surfaces having opposing ogee curves and having a contracted portion of the neck co-incident with the convex parts of each ogee curve with divergent walls on each side of said contracted portion thereby reducing to the minimum the contacting surfaces of the bulb and the capillary, the diverging walls and the capillary forming a 50 pocket adjacent said contracted part for a binding material.

55 In witness whereof, I have hereunto subscribed my name.

MOSES E. CHENEY.

CERTIFICATE OF CORRECTION.

Patent No. 1,773,950.

Granted August 26, 1930, to

MOSES E. CHENEY.

It is hereby certified that error appears in the printed specification of the above numbered patent requiring correction as follows: Page 2, line 39, in the claim, for the word "bulb" second occurrence read tube; and that the said Letters Patent should be read with this correction therein that the same may conform to the record of the case in the Patent Office.

Signed and sealed this 21st day of October, A. D. 1930.
